[57] **CLAIM**

The ornamental design for a holder for floss or similar articles, as described and shown.

DESCRIPTION

FIG. 1 is a perspective view of a holder for floss or similar article showing my new design;

FIG. 2 is a side elevational view;

FIG. 3 is an edge view of the holder for floss or similar article.

The side and edge of the holder not shown are the same in appearance as the side and edge shown in FIGS. 2 and 3 respectively.
